UNITED STATES PATENT OFFICE.

CLARENCE B. FOSTER, OF DAYTON, OHIO, ASSIGNOR TO THE NATIONAL CASH REGISTER COMPANY, OF DAYTON, OHIO, A CORPORATION OF OHIO, (INCORPORATED IN 1906.)

ELECTRIC CASH-REGISTER.

988,327.

Specification of Letters Patent.

Patented Apr. 4, 1911.

Application filed May 31, 1907. Serial No. 376,699.

To all whom it may concern:

Be it known that I, CLARENCE B. FOSTER, a citizen of the United States, residing at Dayton, in the county of Montgomery and 5 State of Ohio, have invented certain new and useful Improvements in Electric Cash-Registers, of which I declare the following to be a full, clear, and exact description.

This invention relates to improvements in 10 recording machines and has more particular relation to that class of recording machines shown and described in pending United States application Serial No. 359,790, filed Feb. 28, 1907 by Joseph P. Cleal wherein a 15 plurality of banks of controlling keys are each provided with a traveling rack bar, electrically operated forward and backward a predetermined distance to send a predetermined number of electrical impulses to a 20 recording machine which is distantly located from said controlling key board, these impulses being used to set and operate the recording mechanism.

The general object of the invention is to 25 provide an improved system of electric wiring whereby the use of one wire besides a common return wire will be sufficient for any number of banks of controlling keys, whereas heretofore one wire for each 30 separate bank has been considered the minimum in this class of machines.

Another object is to provide a system of 35 relays in the main circuit to control a so-called "bank selector" which is advanced step by step to set the recording mechanism so that the impulses from each bank of 40 controlling keys will be utilized by its own individual receiving mechanism.

With these and incidental objects in view 45 the invention consists in certain novel features of construction and combination of parts the essential elements of which are set forth in appended claims and a preferred form of embodiment of which is hereinafter described with reference to the drawings which accompany and form part of this 50 specification.

Of said drawings: Figure 1 is a vertical elevation through the key board and devices 55 controlled thereby. Fig. 2 is a vertical elevation of the distant recording mechanism. Fig. 2^a is a detail view of the "bank selector" slide. Fig. 3 shows the operating mechanism for operating the recording mechanism, and Fig. 4 is a diagram of the electric

circuits. Fig. 5 is a top plan view of the keyboard.

There is herein shown only a recording device but it is to be understood that it could very easily be converted into a registering and indicating device or a combination of all three and that the use of all of these species of accounting devices is regarded as within the scope of the invention.

In the drawings forming part of this specification there is shown only one bank of keys and devices operated thereby, but the wiring diagram excepting that for the recording mechanism is shown applied to two banks, it being understood that in practice a greater number will be used, all of which are however, exact duplicates of those shown.

Banks of keys are provided, the inner ends of which when depressed are adapted to be 75 in the path of longitudinally sliding bars. The depression of any key of the bank serves to close a circuit through one of a pair of solenoid magnets which serves to drive the longitudinal bar referred to in one 80 direction to an extent dependent on the key depressed. When the desired movement has been completed in one direction the circuit through the solenoid magnet as described is 85 broken and a second circuit is made through the other of the pair of solenoid magnets 90 above referred to, which serves to return the longitudinal slide to its normal position when the second circuit is broken in its turn. By means of a pair of make and break contacts operating with said longitudinal slide, 95 impulses corresponding in number to the value of the key depressed are sent to the recording machine to be utilized to set the printing racks correspondingly.

To accomplish the object of this invention polarized relays are employed to operate the different devices in the recording machine. The armatures of the relays which are used to operate the printing racks and the motor 100 switch of the recording machine are polarized for the north pole and will be attracted by their relays when a current is passed through said relays in one direction, but will not be attracted when a current of the reverse direction is used. The armature of the "bank selector" operating magnet is polarized for the south pole so that said magnet, when connected in parallel with the printing rack relays, will be operated only by a 110

current flowing in a direction which will be ineffective on the printing rack relays. Thus it will be understood that by sending impulses over the line in one direction the printing rack relay corresponding with whichever bank of controlling keys is being operated will be operated to set said rack to a position corresponding to the value of the key depressed without affecting the "bank selector" magnet; then by sending a current of the reverse direction over the same lines (using the common return wire for the positive side of the battery), the "bank selector" magnet will be energized to operate the "bank selector" mechanism without affecting the printing rack relays.

Referring to Fig. 1 it will be seen that there is provided a bank of keys 10 numbered from one to nine inclusive which are adapted to be separately depressed and pins 11 carried thereby serve to move a detent 12 provided with slots 13 for locking the key in depressed position. To this end the detent 12 is mounted on parallel arms 14 and 15 pivoted to the key frame. The arm 15 has an arm 16 extending rearwardly from its pivot and adapted to be engaged by a bell crank latching pawl 17 to latch the detent 12 and the operated key in their operated position. The latching pawl 17 is pivoted to the frame of the machine and has on its rearwardly extending portion a laterally extending pin 18 which when a key is depressed will assume a position like that shown in dotted lines in Fig. 1.

Pivoted at 20 on an upward extension of a sliding rack bar 23 is a spring trip pawl having at its forward end a laterally extending beveled flange projection 19 and also having a downwardly extending heel 21 which abuts the edge of the upward extension of the rack 23. Between the heel 21 and an ear 22 on the rack 23 is interposed a spring which tends to force the projection 19 upwardly. When the pin 18 is in the dotted line position and the rack 23 starts forward, the flange 19 will ride under said pin, compressing the spring of the trip pawl, and when the flange 19 has passed the pin 18, the trip pawl will assume its normal position. At the final return movement of the rack 23 the beveled under edge of the beveled flange 19 will cam the pin 18 downward and force the bell crank pawl 17 from under the projection 16 of the arm 15, thereby releasing the detent 12 and the depressed key, both of which will be restored to their normal positions by their respective springs. The heel 21 on the return of the rack 23 abuts against the upward extension of said rack 23 and prevents the trip pawl from swinging on its pivot during the camming downward of the pin 18. The arm 16 of the arm 15 also serves to operate a series of contacts (see Fig. 1) each time a key is de-

pressed, the object of which will be herein-after explained.

The rack 23 is mounted and slides upon two pins 24 attached to the framework of the machine. When a key is depressed, the detent 12 which as before stated is rocked on the parallel arms 14 and 15, and the pin 290 strikes the upper end of a vertical plate 31 and depresses the same slightly. This plate is longitudinally extended at its lower end as indicated at 32 is carried by parallel arms 33 and 34, pivoted at 35 and 36 to the longitudinally sliding rack bar 23. When the plate 31 is depressed the projection 38 thereon will be moved downward from in front of the slide 39 mounted on pins 40 and 41, the said pins being also carried by the slide 23. The parallel arm 34 is bell crank in form having an upward extension 34a. Between it and a struck up part of slide 39 is a coiled spring 42 tending to move the slide 39 forwardly. When the plate 31 is depressed it moves slightly rearward as will be seen from the direction of the parallel arms 33 and 34 and finally the depending projection of the slide 39 passes over the projection 38 of the plate 31 and locks the same in depressed position. The extension 32 of the plate 31 has a fiber flange 44 on which is mounted a pin 45. In the normal position as shown in Fig. 1 the pin 45 engages and slightly elevates the contact spring 46 and the flange 44 is directly over and slightly depresses the contact spring 47, the third contact spring 48 is provided directly under the spring 47 and all of the three springs mentioned are insulated from each other and mounted on a standard 49. When the depression of the key 10 moves the extension 32 of the plate 31 downward, the spring 47 being under the flange 44 will also be moved downwardly into contact with spring 48 and a circuit will then be closed through driving solenoid magnet 51. This magnet is mounted on a standard from the machine frame and attracts its core 52 between which and the core of a companion solenoid magnet is mounted a toothed rack 53. By a train of gears 54, 55 and 56 the movement of the rack 53 is transmitted to the sliding rack 23. A retarding device consisting of a star wheel 58 mounted upon the shaft of a gear wheel 54 is adapted to be engaged by the jaws 57 of a swingle 59 pivoted at 60 and having a downward extension 61 on either side of which is mounted a compression spring 62.

When the keys 10 are depressed their lower ends are in the path of movement of the slide 39 so that some one of the steps 63 thereof finally engage a depressed key. When this happens the continued forward movement of the slide 23 will not be able to carry slide 39 with it, but the slide will remain stationary so that projection 38 of

the extension 32 of plate 31 has a relative movement forward as compared with slide 39. The projection 38 will finally pass forward of slide 39, the spring 42 will then 5 rock the parallel arms 32 and 34 and as flange 44 will then move upwardly the contact spring 47 will move away from spring 48 thereby finally breaking the circuit of solenoid magnet 51. It will be remembered 10 that contact spring 46 is under slight tension tending to move it downwardly so that when the pin 45 on flange 44 moves downwardly the spring 46 will also move but as spring 47 moves downwardly to the same extent no contact will then take place. When, 15 however, the plate 31 is raised by contact of a depressed key with slide 39, the spring 47 will also raise under its own tension and be brought in contact with the spring 46 as the flange 44 is in its forward position and the pin 45 is out of position to hold up the spring. This closing of contacts 46 and 47 serves to energize the second solenoid magnet 71 which is adapted to return the slide 20 25 23 to its normal position. With this object mechanism precisely similar to the mechanism described in connection with magnet 51 is provided, the same consisting of a core 72 which as before stated is attached to the toothed rack 53.

It will be seen that when springs 46 and 47 are brought into contact, that slide 23 will be returned to normal position and when such position is reached, pin 45 on flange 44 30 35 will engage contact spring 46 and move it away from spring 47, thereby finally breaking the circuit of solenoid magnet 71 and stopping the entire mechanism in normal position. To transmit the differential movement 40 of the various slides 23 to the recording mechanism a series of contacts 111 and 112 are provided directly under the flanged lower part of the extension 32 on plate 31. These springs 111 and 112 are insulated 45 from each other and carried in standard 49 and normally the scallops 113 are entirely out of contact with the said springs. When, however, the arms 33 and 34 are rocked and the plate 31 descends the scallops will be depressed far enough so that the projections 50 thereof will engage the upper end of the contact spring 112 and depress it to contact with spring 111. It will therefore be seen that as the slide 23 moves forwardly a succession of contacts of springs 111 and 112 55 will be made depending upon the extent of movement of said slide as controlled by the particular key which has been depressed.

The recording mechanism is shown in 60 Fig. 2 and comprises a series of printing slides 120 mounted upon pins 121 and having elongated slots therein permitting longitudinal movement thereof. The forward under edges of said slides are provided with 65 rack teeth 122 which are engaged by toothed

segments 123 pivoted upon a shaft 124 and having ratchet teeth 125 formed thereon. Mounted on a shaft 126 are arms 127 carrying at their outer ends spring jaws 128 which engage ratchet teeth 125 to advance 70 the segments 123 and through them the slides 120 step by step. Secured to the arms 127 are armatures 129 of magnets 130. A spring 131 tends to force the arms 127 upward against a stop rod 132. From the 75 above description it will be seen that each time one of the magnets 130 is energized its corresponding rack 120 will be advanced one step. Upon the forward upper edge of the racks 120 are formed type 133 from naught 80 to nine inclusive. A pin 134 carries a supply roll of blank paper 135 which is drawn over two guide pins 136 to a storage roller 137 which is provided with a toothed wheel 138. A feed pawl 139 is attached to the platen 85 arm 140 and is adapted to feed the strip forward a short distance at each operation of said platen arm. A retaining pawl 141 is provided to prevent backward movement of said toothed wheel 138. A gear 142 transmits the movement of the wheel 138 through gear 143 to the roller 144 over which and three guide rollers 145 the ink ribbon 146 passes. The printing platen 147 is forced 90 against the type to take an impression therefrom by a spring 148 but is normally held restrained by a cam 149 mounted upon a driving shaft 150. When the shaft 150 is rotated in the direction of the arrow in Fig. 2 the platen arm 140 will be released and the 100 spring 148 will force the platen 147 against the type as before stated. A series of spring actuated pawls 151 engaging teeth 151^a of racks 120 are pivoted on a shaft 152 and extend rearwardly as at 153 into the path of 105 a bar 154 which is also pivoted on a shaft 152. At one end of shaft 152 the bar 154 has an extending arm 155 carrying an anti-friction roller 155^a adapted to be operated upon by the cam edge of a cam disk 156. 110 From this construction it will be seen that the racks 120 and segments 123 are prevented from retrograde movement during the return of the pawls 128 over the face of the ratchet teeth 125 and that as soon as the 115 shaft 150 is started the arm 155 will be cammed downward to elevate the bar 154 and positively lock the pawls 128 into the teeth of the racks 120. Two slides 160 are provided one at each side of the machine 120 which carry a restoring rod 161 which abuts the rear edge of the operated racks 120 to restore them to normal position. Said restoring rod 161 is operated by an arm 162 which is pivoted to the frame work of the 125 machine and has connected thereto a link 163 which is provided with an anti-friction roller 164 extending into the cam slot 165 of the cam 156.

The timing of the above described mecha- 130

nism is as follows: When the shaft 150 is rotated in the direction of the arrow (see Fig. 2) the roller 155^a is immediately cammed downward to force the bar 154 upward against all of the projections 153 of the alining and locking pawls 151 thereby locking the printing racks and the "bank selector" slide in their set positions. The cam 149 will now release the platen arm 140 and an impression will be taken from the type 133. The locking pawls will now be released and the restoring rod 161 will be operated to restore all operated racks and the slide 170 to their normal position. As a safeguard against displacement from their normal position during the return of the restoring rod the rack 120 and slide 170 are again locked until the cam 156 is rotated to its home position. During the second half of the revolution of the shaft 150 the printing platen arm 140 is cammed to its normal position thereby tensioning the spring 148 and operating the strip and ribbon feed through the feed pawl 139 as previously explained. Mounted on the farther side of the racks 120 and parallel thereto is a slide 170 (see Fig. 2^a) which is a part of the so called "bank selector". This slide is different from the slides 120 in that it is shorter and has no printing type on its upper edge. It also has a less number of operating and alining teeth and is provided with a downwardly extending contact maker 171 which is insulated from the body of said slide. The operating mechanism for this slide is exactly the same as that for the printing slides 120 excepting that its armature 212 (see Fig. 4) is polarized for the opposite pole as compared with the armatures 129 of the printing rack operating mechanism. Mounted upon the side frame of the machine and insulated therefrom is a series of contacts 172 and a continuous contact 173 over which the contact maker 171 travels. The object of this mechanism is to complete a circuit to each one of the operating magnets 130 successively. The means for driving the shaft 150 is shown in Fig. 3 and consists of a motor 175 connected by a train of gears 176 to said shaft. Mounted on shaft 150 is a stop disk 177 having a notch 178 cut in its periphery adapted to be engaged by an arm 179. This arm is pivoted at 180 and has a fiber roller 181 mounted thereon for operating a pair of spring contacts 182 which are included in the motor circuit. Normally spring pressed against the face of the arm 179 is a spring pawl 183 which is loosely pivoted on the shaft 150 and is adapted to be forced by its spring into the path of the arm 179 when said arm is operated to prevent the arm 179 from returning to its normal position until the shaft 150 has made a complete revolution. A pin 184 carried by the disk 177 limits the

initial movement of the pawl 183. The arm 179 extends forward of its pivot and has mounted thereon an armature 185 which is polarized for the same pole as the armatures 129 of the magnets 130 are. Magnet 186 is energized to attract its armature 185 and release shaft 150 and then operate the spring contacts 182 to close the motor circuit. A spring 187 holds the arm 179 against the periphery of the disk 177 so that as shaft 150 nears its home position the roller 181 will be raised from contact with the contact springs 182 thereby breaking the motor circuit. The arm 179 will at the same time force the pawl 183 which has rotated with disk 177 to its normal position and will form a stop for the disk 177.

Shown in Fig. 1 is a starting key 190 which is spring pressed to its outer position by a spring 191 and is locked in its depressed position by a locking plunger 192. This plunger is operated to release the key 190 by a magnet whose armature is pivoted at 193 and extends over a pin in said plunger. The inner end of the key 190 is adapted when depressed to close a pair of contacts 194.

A relay 195 is shown in Fig. 1 whose armature is pivoted at 196 and is provided with a gravity wiper pawl 197 which when said relay is energized will close contacts 198 and 199 and also contacts 200 and 201 momentarily, after which a rearwardly extending portion of said armature will close contacts 202 and 203 and hold them closed until the relay magnet 195 is deenergized. When the armature returns to its normal position the wiper pawl 197 will wipe by the end of contact 198 without causing any motion of said contact.

Referring to Fig. 1 it will be seen that when a key is depressed and the arm 16 of arm 15 is elevated, said arm 16 will engage and raise contact 209 and by reason of the fiber insulating piece 291 interposed between said contact and contacts 207 and 204 will also raise said latter contacts, and the following will result; contacts 204 and 205 will be parted, contacts 206 and 207 will be closed, contacts 208 and 209 will be closed and contact 209 will be parted from contact 210. This series of contacts is necessary for the following reasons; the rack bars 23 of the different banks of controlling keys are intended to operate successively beginning with the first bank at the right. The relays 195 are directly connected to the main lines and are operated as soon as the current is allowed to reach them so that if the main circuit is not broken just before it reaches each of these relays they would all be operated together which would cause a wrong operation of the machine so the series of contacts above mentioned is provided at each bank to compel the relays 195 to op-

105

110

115

120

125

130

erate directly after its corresponding bank is operated except when no key in said bank is operated when it will operate directly after the preceding relay 195 has been operated.

The wiring diagram (see Fig. 4) will be described, assuming that a key in the cents bank has been depressed and no key depressed in the dimes bank. A battery 215 or 10 other generator is provided to furnish current for the system. A key being depressed in the cents bank the contacts 204 to 210 will be in the position shown and the contact spring 47 in contact with spring 48 as 15 will be remembered and after the starting key 190 is depressed and latched in its depressed position a circuit is made as follows; from the generator 215 through wire 216, contacts 194, wire 217, wire 218, contact 207, contact 206, wire 219, contact 47, contact 48, wire 220, solenoid magnet 51, wire 221, contact 208, contact 209, wire 222, wire 223, back to the generator. This it will 20 be remembered serves to energize the magnet 51 to move the rack 23 forward until slide 39 strikes a depressed key. When slide 39 abuts the key, contacts 47 and 48 will be parted and contact 47 will be thrown into connection with contact 46, the returning circuit 25 is then complete as follows: generator 215, wire 216, contacts 194, wire 217, wire 218, contact 207, contact 206, wire 219, contact 47, contact 46, wire 224, solenoid magnet 71, wire 225, wire 221, contact 208, contact 209, wire 222, wire 223 back to the generator. As the scalloped plate moves over the contacts 111 and 112 they will be brought together a number of times depending on the key depressed and the recording circuit will 30 then be complete as follows: generator 215, wire 216, contacts 194, wire 217, wire 218, contact 207, contact 206, wire 219, wire 226, contact 112, contact 111, wire 227, wire 228, wire 229, wire 230 to magnet 130 of the 35 cents printing rack, wire 231 to first individual contact piece 172, contact maker 171, continuous contact 173, wire 232, "bank selector," magnet 233, wire 234, wire 235, wire 221, contact 208, contact 209, wire 222, wire 223 back to the generator. This will 40 advance the cents printing rack proportionately to the key depressed but will not operate the magnet 233 because the armature 212 of said magnet is polarized oppositely to 45 those of the magnets 130. It will be remembered that on the final return movement of the rack 23 the arm 16 (see Fig. 1) is released and the series of contacts 204 to 210 assume their normal position as shown in 50 connection with the dimes bank (see Fig. 4) the depressed key and detent 12 of the operated bank are also returned to their normal position at this time and the following circuit will be formed to energize the relay 55 195; generator 215, wire 216, contacts 194,

wire 217, wire 218, contact 204, contact 205, wire 236, wire 237, wire 238, relay 195, wire 239, wire 240, wire 241, contact 210, contact 209, wire 241, wire 222, wire 223 back to the generator. This circuit will energize the 70 relay 195 and as before explained will make a momentary contact between contacts 198 and 199 and contacts 200 and 201. This will close a circuit to the "bank selector" as follows; generator 215, wire 216, contacts 194, 75 wire 217, wire 218, contact 204, contact 205, wire 236, wire 237, wire 242, contact 198, contact 199, wire 243, wire 234, to "bank selector" magnet 233, wire 232, continuous contact 173, contact maker 171, first individual contact 172, wire 231, first magnet 130, wire 230, wire 229, wire 228, wire 244, contact 201, contact 200, wire 245, wire 241, contact 210, contact 209, wire 222, wire 223 back to the generator. Thus it will be seen 80 that the momentary closing of contacts 198 to 201 cause an impulse to be sent to the recording machine in a reverse direction to those sent by the contacts 111 and 112. This as before stated causes the magnet 233 to be 85 energized to advance the rack 170 forward and causes the contact maker 171 to make contact between the continuous contact 173 and the second individual contact 172. 90 Immediately after the "bank selector" is 95 operated through the closing of the contacts 198 to 201, the armature of relay 195 closes contacts 202 and 203 thereby completing a circuit to the next bank which if a key in said bank were depressed would be a duplication of the circuit for the previously explained bank, but as no key has been depressed (for sake of illustration) circuit will be made as follows: generator 215, wire 216, 100 contacts 194, wire 217, wire 218, contact 204, contact 205, wire 236, wire 237, wire 242, contact 202, contact 203, wire 246, wire 247, wire 248, contact 204', contact 205', wire 249, wire 250, relay 195', wire 251, wire 252, wire 253, contact 210', contact 209', wire 253a, wire 254, wire 240, wire 241, contact 210, contact 209, wire 222, wire 223 back to the generator. This circuit will close the relay 195' and by momentarily closing the 110 contacts 198' and 199' and the contacts 200' and 201' to close the circuit to the "bank selector" as follows: generator 215, wire 216, contacts 194, wire 217, wire 218, contact 204, contact 205, wire 236, wire 237, wire 242, contact 202, contact 203, wire 246, wire 247, wire 248, contact 204', contact 205', wire 249, wire 255, contact 198', contact 199', wire 256, wire 257, wire 234, to "bank selector," magnet 233, wire 232, continuous contact 173, contact maker 171, second individual contact 172, wire 261, to magnet 130 of the dimes bank, wire 262, wire 229, wire 228, wire 258, wire 259, contact 201', contact 200', wire 260, wire 253, contact 210', contact 209', wire 253a, wire 120 125 130

254, wire 240, wire 241, contact 210, contact 209, wire 222, wire 223 back to the generator. This will operate the "bank selector" in the same manner as heretofore explained. The 5 operation as explained in connection with the two banks shown will be repeated for as many banks as there are banks of controlling keys 10. The relay for the last bank will advance the contact maker 171 to the last 10 individual contact 172 which is connected to the starting magnet 186.

Immediately after the "bank selector" is operated by the relay of the last bank, a circuit the same as the one which will now be 15 explained, excepting that it will have to pass through as many series of contacts 204 to 210 as there are banks of keys 10 and number of printing racks 120 will be made to permit the current to energize a starting relay 265. This circuit includes generator 215, wire 216, contacts 194, wire 217, wire 218, contact 204, contact 205, wire 236, wire 237, wire 242, contact 202, contact 203, wire 246, wire 247, wire 248, contact 204', contact 25 205', wire 249, wire 255, contact 202', contact 203', wire 266, wire 267, wire 268, relay 265, wire 269, wire 270, wire 252, wire 253, contact 210', contact 209', wire 253^a, wire 254, wire 240, wire 241, contact 210, contact 30 209, wire 222, wire 223 back to the generator. This will energize the relay 265 whose armature will cause a momentary closing of contacts 274 and 275 and contacts 276 and 277 making a circuit as follows: generator 35 215, wire 216, contacts 194, wire 217, wire 218, contact 204, contact 205, wire 236, wire 237, wire 242, contact 202, contact 203, wire 246, wire 247, wire 248, contact 204', contact 205', wire 249, wire 255, contact 202', contact 40 203', wire 266, wire 267, wire 271, contact 274, contact 275, wire 278, wire 228, wire 229, wire 285, starting magnet 186, wire 286, to the last individual contact 172, contact maker 171, continuous contact 173, wire 232, magnet 233, wire 234, wire 279, contact 45 277, contact 276, wire 287, wire 270, wire 252, wire 253, contact 210', contact 209', wire 253^a, wire 254, wire 240, wire 241, contact 210, contact 209, wire 222, wire 223, back to 50 the generator. This circuit will cause the magnet 186 to be energized to release the arm 179 from the locking disk 177 (see Fig. 3) thereby releasing shaft 150 and closing the contacts 182 which are included in a 55 local motor circuit as follows; battery 290, wire 291, contacts 182, wire 292, through the motor 175, wire 293, to battery. It will be noted that after each relay is energized its circuit remains closed until the supply of 60 current is cut off by the parting of contacts 194.

Immediately after the contacts 274 to 277 are closed the contacts 272 and 273 are closed and a circuit will be made as follows: generator 65 215, wire 216, contacts 194, wire 217,

wire 218, contact 204, contact 205, wire 236, wire 237, wire 242, contact 202, contact 203, wire 246, wire 247, wire 248, contact 204', contact 205', wire 249, wire 255, contact 202', contact 203', wire 266, wire 267, wire 271, contact 273, contact 272, wire 280, magnet 281, wire 282, wire 223 back to the generator. This will energize the magnet 281 which will release the starting key 190 thereby allowing the spring contacts 194 to part and break all 75 circuits to the machine.

The operation of the machine as described is as follows: Keys as desired are depressed and latched in their depressed position by their respective detents. The latching of a 80 key by its detent will operate the series of contacts 204 to 210 to divide the main circuit and connect the operating circuit of its bank. The depressing of a key will also cause the contact 47 to be moved into engagement with 85 the contact 48. After the desired keys are depressed, the starting key 190 is depressed and latched in its depressed position. This key will close the contacts 194 and complete the main circuit to the generator 215. If a 90 key in the cents bank is depressed, the operating mechanism of said bank will be operated as soon as the starting key is depressed. As before explained the depressed keys are released as soon as their rack bars 23 have 95 returned to their normal positions. During the forward movement of the bar 23 impulses are sent to the distant recording device to set the printing bar 120 corresponding to the number of the key depressed. 100 The releasing of the depressed key will release the series of contacts 204 to 210, thereby allowing them to assume their normal position. The current will now pass on to the relay 195 and close said relay. The circuit 105 beyond said relay is broken by the contacts 202 and 203. Thus it will be seen that the main circuit beyond said relay is not complete until after said relay is operated. When the relay 195 is operated it causes the 110 contacts 198 to 201 to send a momentary impulse to the recording device to operate the "bank selector" to complete a circuit to operate the printing bar 120 of the next higher bank. Immediately after the closing of 115 contacts 198 to 201, the contacts 202 and 203 are closed to extend the main circuit to the next bank. If no key in the next bank is depressed contacts 204' to 210' remain in their normal position, thereby extending the 120 main circuit to the next relay. Thus it will be seen that when no key in a bank is depressed, the time required for operation of the mechanism of said bank is saved and the main circuit continues on to the next relay 125 uninterrupted. This same operation is repeated throughout all the banks. The momentary impulse caused by the last relay serves to complete a circuit to the magnet 186. The operation of the last relay 195' 130

extends the main circuit to a separate relay 265. This relay is utilized to close the circuit to the magnet 186 to release the driving device of the recording mechanism and start 5 the motor therefor. After said motor starting circuit is complete the relay 265 closes contacts 272 and 273. This will extend the main circuit to the magnet 281 to release the starting key and break the main circuit. It 10 will be seen that there are only two wires required between the banks of keys and the recording device, where heretofore it has been customary to use one wire for each bank of keys and a common return wire for the complete 15 system.

While the form of mechanism here shown and described, is admirably adapted to fulfil the objects primarily stated, it is to be understood that it is not intended to confine 20 the invention to the one form of embodiment herein disclosed, for it is susceptible of embodiment in various forms, all coming within the scope of the claims which follow.

What is claimed is as follows:

25 1. In a recording mechanism, the combination with a plurality of banks of keys, of a differentially moving element for each bank of keys controlled thereby, means for moving said elements until stopped by a key, means rendered operative when said elements are stopped for returning said elements, and a recording device controlled by said elements.

30 2. In a recording mechanism, the combination with a plurality of banks of controlling keys, of a series of differentially movable elements controlled by said keys, individual means for moving each of said elements successively until stopped by a key, 35 separately operated means rendered operative when said elements are stopped for returning said elements, and a recording device controlled by said elements.

35 3. In a recording mechanism, the combination with a series of manipulative elements, of a recording device, means controller by said elements for causing a differential operation of said recording device, a series of power devices for moving said 40 means in one direction, a second series of power devices thrown into operation by said first series of power devices for moving said means in the reverse direction.

45 4. In a recording mechanism, the combination with recording devices, of a plurality of banks of keys controlling same, differentially movable elements for causing operation of said recording devices to an extent determined by the keys, a series of motor 50 mechanisms for operating said elements and a second series of motor mechanisms thrown into operation by said first series for restoring said elements to their original position.

55 5. In a recording mechanism, the combination with a plurality of banks of control-

ling keys, of a series of printing elements arranged to be set differentially, a series of individual motors for moving said means in one direction; a second series of individual motors for moving said means in the opposite direction and means controlled by the keys for successively rendering said motors operative.

6. In a recording mechanism, the combination with a plurality of banks of keys, a series of printing elements, a series of separately operated means for causing said elements to be set differentially, a series of individual motors for moving said means in one direction, a second series of individual 70 motors for moving said means in the opposite direction and a separate key effecting the operation of both series of motors.

7. In a recording mechanism, the combination with a plurality of banks of keys, of a recorder comprising a series of printing elements, means for causing a differential movement of said elements depending upon the keys depressed, a series of motors for moving said means in one direction and a series of motors for returning said means to their normal position.

8. In a recording mechanism, the combination with a recording device comprising a series of printing elements, of a plurality of manipulative devices for determining the movement of same, a series of latching devices for said manipulative devices, a series of differentially movable means for causing operation of said printing elements, electric power mechanisms for returning said means to their normal positions, and means depending upon the operation of the latching devices of the manipulative devices for energizing said electric power mechanisms.

9. In a recording mechanism, the combination with recording devices, of a plurality of banks of controlling keys, a series of differentially movable elements for causing the operation of said recording devices, motor mechanisms for driving said elements in opposite directions, and circuits for controlling said mechanisms, and themselves controlled by the keys.

10. In a recording mechanism, the combination with a recording device comprising a series of printing elements, of a plurality of banks of keys, a series of differentially movable means for causing the operation of said printing elements, two series of motor mechanisms for moving said means in opposite directions, a circuit for one of said series of motor mechanisms closed by the operation of the keys, and a circuit for the other series of motor mechanisms closed by the completion of movement of the differential means under control of said first series of motor mechanisms.

11. In a recording mechanism, the combination with a recording device comprising

- a series of printing elements, of a plurality of banks of keys, a series of latching detents for latching said keys in their operated positions, a series of differentially movable means 5 for causing the operation of said printing elements, two series of motor mechanisms for moving said means in opposite directions, a circuit for one of said series of motor mechanisms closed by the operation of said latching detents, and a circuit for the other series 10 of motor mechanism closed by the completion of movement of the differential means under control of said first series of motor mechanisms.
- 15 12. In a recording mechanism, the combination with a recording device, of a plurality of banks of keys, a plurality of differentially movable elements under control of said keys and causing operation of said recording device, a series of motors for moving said elements in one direction until stopped by a key, a circuit controlling said series of motors closed by the operation of a key, a second series of motors for returning 20 said elements to normal position, and a circuit for said second series of motors closed when said elements abut the depressed key.
13. In a recording mechanism, the combination with recording devices, a series of 25 elements for causing operation of same, a series of magnets for moving said elements a predetermined distance in one direction, a second series of magnets for returning said elements to their normal positions, and a circuit for said magnets successively closed under control of said elements.
14. In a recording mechanism, the combination with recording devices, of a plurality of banks of keys for controlling same, a series of elements for causing operation of 30 said recording devices, a series of motor magnets for moving said elements a predetermined distance in one direction, a second series of motor magnets for returning said elements to their normal positions, and circuits for said motor magnets successively 35 closed under control of said keys.
15. In a recording mechanism, the combination with a recording device, of a plurality of banks of keys, a plurality of differentially movable elements controlling the recording device, electrically operated motors for operating said elements, a normally open circuit for said motors, a main circuit, 40 a series of contacts for each bank of keys for extending the main circuit beyond said bank, a separate means for completing the main circuit to a generator, and means for operating the said series of contacts to divide the 45 main circuit and connect the motor circuit therewith.
16. In a recording mechanism, the combination with a plurality of banks of keys, a plurality of movable elements, a plurality of 50 motors for operating each of said elements, a

circuit for each of said motors, a main circuit, a series of contacts for each bank of keys for extending the main circuit, means controlled by the depression of the keys for operating the said series of contacts to divide the main circuit and connect said motor circuits therewith, and releasing devices carried by said movable elements for releasing the depressed keys at the return to normal position of the movable elements.

75 17. In a recording mechanism, the combination with a recording device comprising a plurality of printing elements, electric motors and circuits therefor for setting said printing elements, a plurality of banks of keys, differentially movable means for operating the recording device controlled by the keys, an interrupter controlled by said differentially movable means which completes the circuits to the electric motors to energize said motors.

80 18. In a recording mechanism, the combination with a recording device comprising a plurality of printing elements, electric motors and circuits therefor for setting said printing elements, a plurality of banks of keys, differentially movable means for operating the recording device controlled by the keys, an interrupter controlled by said differentially movable means which completes the circuits to the electric motors to energize said motors, and means for returning 85 said printing elements to their normal position.

90 19. In a recording mechanism, the combination with a recording device comprising a plurality of printing elements, electric motors and circuits therefor for setting said printing elements, a plurality of banks of keys, differentially movable means for operating the recording device controlled by the keys, an interrupter controlled by said differentially movable means which completes 95 the circuits to the electric motors to energize said motors, and alining devices 100 for said printing elements.

105 20. In a recording mechanism, the combination with a recording device comprising a plurality of printing elements, electric motors and circuits therefor for setting said printing elements, a plurality of banks of keys, differentially movable means for operating the recording device controlled by the keys, an interrupter controlled by said differentially movable means which completes 110 the circuits to the electric motors to energize said motors and positively operated locking means for said printing elements.

115 21. In a recording mechanism, the combination with a recording device comprising a plurality of printing elements, electric motors and circuits therefor for setting said printing elements, a plurality of banks of keys, differentially movable means for operating 120 the recording device controlled by the keys, an interrupter controlled by said differentially movable means which completes the circuits to the electric motors to energize said motors and positively operated locking means for said printing elements.

125

130

keys, an interrupter controlled by said differentially movable means which completes the circuits to the electric motors to energize said motors, a printing platen and means for feeding a paper strip and an inking ribbon at each operation of the machine.

22. In a recording mechanism, the combination with a plurality of printing elements, and means for setting said printing elements, of a plurality of banks of keys for controlling said means, a movable contact maker, connections controlled by said contact maker for bringing said printing setting means under control of banks of said keys, a motor for operating said contact maker, a circuit for said motor and means under the control of the keys for completing said circuit.

23. In a recording mechanism, the combination with a plurality of printing elements, a series of polarized magnets for setting said printing elements, of a plurality of keys controlling said magnets, a selecting device, a single polarized magnet for operating said selecting device, a circuit for all of the polarized magnets under control of the selecting device, means for causing a current to pass through said circuit in one direction to energize the polarized magnets of the printing elements without affecting the selecting device operating magnet and a separate means for causing a current to pass through said circuit in an opposite direction to energize the operating magnet of the contact maker without affecting the operating magnets of the printing elements.

24. In a recording mechanism, the combination with a recording device, a series of printing elements, a plurality of manipulative devices controlling said elements, a series of motors for said printing elements, a selecting device, a separate motor for operating said selecting device, a contact maker operating with said selecting device to successively connect each one of the series of motors for the printing elements in parallel with the motor for the selecting device, a circuit for all of said motors, a circuit and connections so arranged as to cause the current to flow in different directions at different times to operate all of said motors alternately or successively as determined by said manipulative devices.

25. In a recording mechanism, the combination with a recording device, of a plurality of banks of keys controlling said device, a main circuit, a series of contacts for each bank of keys for extending the main circuit beyond said bank, a selecting device for the recording device, a series of relay magnets for controlling said selecting device and for extending the main circuit beyond said relay magnets.

26. In a recording mechanism, the com-

bination with a recording device and an operating device therefor, of a plurality of printing elements, a plurality of banks of keys, electrically operated devices controlling the positioning of the printing elements, individual circuits for said electrically operated devices, a main circuit, a series of contacts for dividing the main circuit and connecting said individual circuits thereto, a selecting device for the recording device, a series of relays controlling said selecting device, a second series of contacts for extending the main circuit beyond the bank to its corresponding relay, separate contacts for each relay for extending the main circuit to a succeeding bank of keys, means for controlling the operating device of the recording device, a magnet for controlling said means, a relay for operating said magnet, a starting key for closing the main circuit, a releasing device for said key and contacts operated by the last mentioned relay for causing operation of the releasing device of the starting key to break the main circuit.

27. In a recording mechanism, the combination with controlling mechanism, comprising banks of keys, and mechanism movable differentially under control of said keys, of means rendering said differentially movable mechanism inoperative, except the mechanism of lowest denomination, means operated by the final increment of movement of any differentially movable mechanism for rendering operative the mechanism of the next higher order, and recording mechanism controlled by said controlling mechanism.

28. In a recording mechanism, the combination with controlling mechanism, comprising differentially movable denominational devices, and banks of keys controlling same, of means rendering said devices except that of lowest denomination inoperative, means operated by the final movement of any denominational device for rendering operative the denominational devices of the next higher order, and distant denominational recording devices successively operated in correspondence with the differentially movable devices.

29. In a recording mechanism, the combination with controlling mechanism comprising differentially movable denominational devices, and banks of keys controlling same, of electrical means including circuits for operating said denominational devices, means for normally breaking the circuit to all said means except that of lowest order, means operated by the final increment of movement of any denominational devices for closing the circuit of the means of next higher order, and accounting mechanism controlled by said denominational devices.

30. In a recording mechanism, the combination with controlling mechanism, com-

prising banks of keys, and differentially movable denominational devices controlled thereby, of accounting mechanism having a differentially movable element for each of 5 said devices, each of said elements being arranged to be controlled by corresponding devices, means normally rendering each of said elements and devices inoperative except those of lowest denomination, and 10 means controlled by each of said denominational devices for rendering operative the device of next higher order.

31. In a recording mechanism, the combination with controlling mechanism, comprising banks of keys and differentially movable denominational elements controlled thereby, of motors for each of said elements, means rendering normally inoperative all the motors except those of lowest demonina- 15 tion, means operated by each element for rendering operative the element of next higher order, and accounting mechanism controlled by said movable elements.

32. In a recording mechanism, the combination with a transmitting instrument including denominational elements, of a distant receiving instrument including denominational elements corresponding to those of the transmitting instrument, a single electric circuit connecting the transmitting and receiving instruments, means for controlling said circuit successively from the several denominational elements of the transmitting instrument, and means for bringing the several denominational elements of the receiving instrument successively under the control of said connecting electric circuit.

33. In a recording mechanism, the combination with a transmitter including denominational elements, of a distant receiver comprising denominationl elements corresponding to those of the receiver, an electric circuit connecting said transmitter and said receiver, means for connecting the transmitter denominational elements successively into a condition controlling said circuit, devices for connecting the receiver elements into a condition under control of said circuit, and means for automatically retaining 50 in the receiver an entry of transactions on the transmitter.

34. In a recording mechanism, the combination with a transmitter including denominational elements, of a receiver also including denominational elements, an electric circuit connecting said transmitter and receiver, local circuits controlled by the denominational elements of the transmitter, means for successively connecting said local 55 circuits to said connecting circuit, and means for automatically bringing said receiver elements successively under control of said connecting circuit.

35. In a recording mechanism, the combination with a transmitter including denominational elements, of a receiver also including denominational elements, an electric circuit connecting said transmitter and receiver, local circuits controlled by the denominational elements of the transmitter, means for successively connecting said local 55 circuits to said connecting circuit, and means for automatically bringing said receiver elements successively under control of said connecting circuit.

36. In a recording mechanism, the combination with a transmitter, of a receiver including denominational elements, an electric connection between said transmitter and receiver, means for controlling said electric connection by a denominational element 70 of the transmitter, means actuated by said transmitter element for shifting the control of said connection to a succeeding denominational element, and means for automatically bringing the denominational elements 75 of the receiver successively under control of said electric connection.

36. In a recording mechanism, the combination with a transmitter, of a receiver including denominational elements, an electric connection between said transmitter and receiver, means whereby said transmitter causes impulses to pass over said connection to actuate a denominational element of the receiver, and devices whereby an impulse 80 having characteristics distinct from said actuating impulses brings another denominational element under control of said transmitter.

37. In a recording mechanism, the combination with a transmitter, of a receiver having denominational elements, an electric connection between said transmitter and one of said receiver denominational elements, means under control of said transmitter for sending impulses over said connection to actuate said connected one of the receiver denominational elements, means for transmitting over said connection an impulse having characteristics distinct from said actuating 95 impulses, with devices whereby said last mentioned impulse brings a succeeding denominational element of the receiver under control of said electric connection.

38. In an accounting mechanism, the combination with a plurality of movable elements, and means for successively actuating same differentially, the said means being under the control of said elements.

39. In an accounting mechanism, the combination with a plurality of movable denominational elements, and means for successively actuating same differentially, each element controlling the actuation of the element of the next denomination.

40. In an accounting mechanism, the combination with a transmitting instrument having differentially movable elements, of a receiving instrument having corresponding elements, and a selector for the elements of the receiving instrument controlled by the elements of the transmitting instrument.

41. In an accounting mechanism, the combination with a transmitting instrument having differentially movable elements, of a receiving instrument having corresponding elements, and a selector given a step by step movement by the elements of the transmitting instrument for controlling the elements of the receiving instrument.

42. In an accounting mechanism, the combination with a transmitting instrument having differentially movable denominational elements, of a receiving instrument having corresponding elements, and a selector actuated by the elements of the transmitting instrument for successively controlling the elements of the receiving instrument.
- 10 43. In an accounting mechanism, the combination with a transmitting instrument having differentially movable elements, of a receiving instrument having corresponding elements, and a magnetically operated selector actuated by the elements of the transmitting instrument for successively controlling the elements of the receiving instrument.
- 20 44. In an accounting mechanism, the combination with a transmitting instrument having differentially movable elements, of a plurality of solenoids for actuating said elements, a receiving instrument having elements corresponding to those of the transmitting instrument, and a magnetically operated selector actuated by parts of the transmitting instrument for successively controlling the elements of the receiving instrument.
- 30 45. In an accounting mechanism, the combination with a transmitting instrument having differentially movable elements, of a plurality of solenoids for actuating said elements, a receiving instrument having elements corresponding to those of the transmitting instrument, means including a selector for connecting the elements of said instruments, and means controlled by said movable elements of the transmitting instrument for intermittently actuating said selector.
- 45 46. In a recording mechanism, the combination with a transmitting instrument, of a distant receiving instrument including differential receiving instrument including differential nominational elements, means for operating said elements including a successively operated circuit closer controlled by the transmitting instrument, and means for taking an impression from said elements, the said impression means being controlled by the circuit closer.
- 55 47. In a recording mechanism, the combination with a transmitting instrument, of a distant receiving instrument including differentially movable type carriers, electrical devices for setting said type carriers, a contact maker controlled by the transmitting instrument for establishing circuits through said devices, means for taking an impression from the type carriers after they are set, and a motor controlled by said contact maker for operating the impression means.
- 60 48. In a recording mechanism, the combination with a plurality of differentially movable type carriers, of means including a circuit closer for successively setting said type carriers, and means for taking an impression from the type carriers controlled by the circuit closer.
- 70 49. In an accounting machine, the combination with a plurality of differentially movable elements, of means for operating said elements, and means for first locking said elements in their set position, then restoring them to normal position and finally locking them temporarily in their restored position.
- 75 50. In an accounting machine, the combination with a plurality of differentially movable type carriers, of means for operating said elements, a series of alining pawls, a cam for first locking said pawls in engagement with the type carriers in their operative position, then restoring said carriers to normal position and finally locking the pawls temporarily in engagement with the type carriers in their restored position to prevent rebound of same.
- 80 51. In a machine of the class described, the combination with a plurality of differentially movable elements, of means for successively actuating the same during an operation of the machine, manipulative devices for determining the extent of movement of said elements, and means rendered operative by said elements when the latter have moved their determined extent for returning said elements to normal position.
- 85 52. In a machine of the class described, the combination with a plurality of differentially movable elements, of power devices for successively actuating the same during an operation of the machine, keys for determining the extent of movement of said elements, and additional power devices rendered operative by said elements when the latter have moved their determined extent for returning said elements to normal position.
- 90 53. In a machine of the class described, the combination with a plurality of differentially movable elements, of electric power devices for successively actuating the same during an operation of the machine, keys for determining the extent of movement of said elements, additional electric power devices for returning said elements to normal position, and circuits for both of said power devices under the control of said keys.
- 95 54. In a machine of the class described, the combination with a plurality of differentially movable elements, of electric power devices for successively actuating the same during an operation of the machine, keys for determining the extent of movement of said elements, additional electric power devices for returning said elements to normal position, circuits for both sets of power devices, and means carried by the differentially movable elements and controlled by the keys for closing said circuits.

55. In a machine of the class described, the combination with a plurality of differentially movable elements, of electric power devices for successively actuating the same 5 during an operation of the machine, depressible keys for determining the extent of movement of said elements, circuits for said power devices, spring drawn plates mounted upon the differentially movable elements 10 and operated by the keys for closing the circuits through the power devices, and locking devices also mounted upon the differentially movable elements for locking the circuit closing plates in their operated positions, the said locking devices 15 being constructed to contact with the depressed keys and be thereby moved to release the circuit closing plates.

56. In a machine of the class described, 20 the combination with a plurality of differentially movable elements, of electric power devices for successively actuating the same during an operation of the machine, depressible keys for determining the extent of 25 movement of said elements, additional electric power devices for returning said ele-

ments to normal position, circuits for both sets of power devices, spring drawn plates mounted upon the differentially movable elements and operated by the keys for closing 30 the circuits through the first mentioned power devices, locking devices also mounted upon the differentially movable elements for locking the circuit closing plates in their operated positions, the said locking devices 35 being constructed to contact with the depressed keys and be thereby moved to release the circuit closing plates, circuits for the power devices for returning the differentially movable elements established by the 40 released circuit closing plates, and means carried by the circuit closing plates for breaking the last mentioned circuits as the differentially movable elements reach normal or home position. 45

In testimony whereof I affix my signature in the presence of two witnesses.
